(57) **CLAIM**

The ornamental design for a cultivator frame, as shown and described.

DESCRIPTION

FIG. 1 is a perspective view of a cultivator frame showing my new design;

FIG. 2 is a front side view thereof;

FIG. 3 is a rear side view thereof;

FIG. 4 is a left side view thereof;

FIG. 5 is a right side view thereof;

FIG. 6 is a top view thereof; and

FIG. 7 is a bottom view thereof; and,

FIG. 8 is a perspective view thereof.

The broken lines shown in the drawing view of FIG. 8 are for illustrative purposes only and form no part of the claimed design.
